UNITED STATES PATENT OFFICE.

GUSTAVE A. CARLSON, OF DETROIT, MICHIGAN.

SASH-REGULATING DEVICE.

Application filed January 14, 1924. Serial No. 685,973.

To all whom it may concern:

Be it known that I, GUSTAVE A. CARLSON, a citizen of the United States, residing at Detroit, in the county of Wayne and State of Michigan, have invented certain new and useful Improvements in Sash-Regulating Devices, of which the following is a specification, reference being had therein to the accompanying drawings.

10 This invention relates to a sash regulating device of that type adapted to be used in the wall or door of an automobile body for raising and lowering a sash or other closure relative to a window or door frame opening. The device may also be used in general for raising or lowering any member when such member is to be automatically held in adjusted position.

My invention also has special reference to 20 that class of sash regulators wherein a flexible member is articulated relative to the lower edge of the sash and an operating mechanism provided for actuating the flexible member, the operating mechanism including automatic means for holding the 25 flexible member in adjusted position.

The primary object of my invention is to provide the sash regulating device of the above type embodying a comparatively flat 30 structure that may be easily and quickly mounted in a sash or closure well for raising and lowering a sash or closure at or in the well, the device including an operating mechanism which will positively hold the 35 sash or closure in adjusted position.

Another object of this invention is to provide a sash regulating device with an operating mechanism including eccentric gearing arranged so that it constitutes an automatic lock for preventing a driven rotary 40 member from rotating because of a load sustained thereby.

A further object of this invention is to provide a sash regulating mechanism including a wide sash supporting member which will prevent a sash from binding because of other than a true perpendicular 45 movement in a door or window frame.

A still further object of my invention is

to provide a novel chain and wheel drive 50 mechanism wherein the relation of the wheel and chain is such that any load on the chain is sustained, independent of the actual driving connection between the wheel and chain, consequently the driving connections are 55 not subjected to the usual wear and tear incident to a load being constantly and directly supported from such driving connections.

The above and other objects are attained 60 by a durable, compact and easily assembled mechanism that will be hereinafter specifically described and then claimed, and reference will now be had to the drawings, 65 wherein—

Figure 1 is a front elevation of a frame having a sash adjustable therein by a regulating device in accordance with my invention;

Fig. 2 is a vertical cross sectional view of 70 the same;

Fig. 3 is a horizontal sectional view taken on the line III—III of Fig. 1;

Fig. 4 is an enlarged front elevation of 75 a wide member for supporting a sash;

Fig. 5 is a plan of the same;

Fig. 6 is an enlarged front elevation of 80 the operating mechanism of the sash regulating device, with a cover of the casing removed;

Fig. 7 is a similar view of the operating mechanism with the chain engaging wheel removed;

Fig. 8 is a horizontal sectional view taken 85 on the line VIII—VIII of Fig. 6, with the casing cover in place;

Fig. 9 is a vertical cross sectional view of the operating mechanism of the device, and

Fig. 10 is a horizontal sectional view of 90 the same.

Reference will first be had to Figs. 1 to 5 inclusive and the reference numeral 1 denotes, by the way of an example, a frame or wall having grooves or guides 2 for a sash or closure 3 which is adapted to be raised 95 and lowered in the frame and automatically held in an adjusted position within the frame. The sash 3 is movable in and out of

a well 4 in the lower part of the frame and the well may be formed by panels or wall boards 5 and 6 carried by the frame 1.

Mounted in the well 4 and attached to 5 transverse members 7 and 8, against the panel 5, is a vertically disposed sheet metal casing 9 having a cover 10 attached to the casing 9 by screws 11 or other fastening means and said casing is preferably located 10 centrally of the well 4 and at the inner side of the sash 3 without interfering with movement of said sash in the guides 2 of the frame 1.

The upper end of the casing 9 is stamped 15 or pressed to provide a cylindrical housing 12 and the cover 10 has a corresponding housing 13 which cooperates with the housing 12 in forming a compartment for the greater part of the operating mechanism 20 of my sash regulating device. Concentric of the housings 12 and 13 are bearings 14 and 15 respectively and journaled in said bearings is a binding arbor or shaft 16 having a shank or tang 17 on which is mounted 25 a crank or operating handle 18. The bearing 15 extends through the panel 5 so that the crank or handle 18 may be operated at the inner side of the door or wall.

Suitably fixed on the arbor 16 is a compound wheel which may be made of two 30 parts cut and stamped from metal with the parts thereof spot welded or otherwise connected together, but in some instances the compound wheel may be a homogeneous 35 mass with the periphery thereof having a configuration which will serve two purposes. As shown, one part of the compound wheel is in the form of a chain driving member 19 and the other part in the form of a chain 40 supporting member 20. The periphery of the chain driving member 19 is provided with equally spaced recesses or pockets 21 for chain studs 22, said studs being carried intermediate the ends of the links 23 and 45 24 pivotally connected together by rivets or studs 25. Each alternating link 24 may be composed of two parts held together by the studs 22 and the ends of the two parts may be pressed and apertured so as to provide 50 opposed ears between which may extend the apertured ends of the links 23. With the links 23 and 24 cut or stamped from sheet metal the chain can be easily and quickly made and its links readily articulated to 55 afford a comparatively flat flexible member and one end of said member is adapted to support the sash 3. For this purpose an end link of the chain is provided with a right angular tubular extension 26 which 60 in some instances may be connected direct to a bottom rail 27 of the sash 3, or may be provided with a roller 25^a to roll against a bottom channel rail 27 on the lower edge of the sash 3. I prefer to fix a wide sash 65 supporting member 28 on an angular ex-

tension 26^a of the lowermost link 23 and provide the ends of the supporting member 28 with spools or flanged rollers 29 on which the rail 27 rests for supporting the sash 3 in the guides 2. The supporting member 70 28 is in the form of a long head or beam which will provide a long support for the sash relative to the chain and in consequence of this long support the sash will be evenly supported for uniform movement in the 75 guides 2, it being practically impossible for the sash 3 to cant and bind against the guides during its movement. This is also brought about by the casing guiding the chain and by positioning the sash regulating device so that the raising and lowering 80 end of the chain will be approximately intermediate the ends of the rail 27.

The chain supporting member 20 has its periphery formed with flat sides or facets 85 30 and as shown in Fig. 6, the member is hexagonal so that two or more of the facets 30 may at all times cooperate in supporting two or more links of the chain. This chain supporting member will sustain the weight 90 of the sash through the medium of the chain and relieve the chain driving member 19 of stresses and strains, particularly at its driving connections with the chain.

Since one end of the chain is free provision 95 has been made for guiding the chain in its movement so that there will be no danger of accidental displacement of the chain relative to the compound drive wheel on the arbor 16. The cover 10 being fastened directly to the casing 9 has its longitudinal edges off-set, as at 31, to cooperate 100 with the edges 32 of the casing 9 in forming longitudinal channels 33 for the chain, the channel extending up over the compound 105 wheel, as best shown in Figs. 6 and 9. In addition to the channel guide for the chain the casing 9 has a depressed way or groove 34 providing clearance for ends of the rivets 25 and studs 22, and it is the channel guide 110 and groove which retains the supporting end of the chain always perpendicular for supporting the sash properly in the sash 115 guides 2.

Mounted on the arbor 17 in the housing 12 of the casing 9 is an eccentric 35 and loosely mounted on said eccentric is a toothed inner clutch member 36 normally engaging a toothed outer clutch member 37 which is fixed in the housing 12 by any suitable means. Attached to the side face of the outer clutch member 37, by spot welding or other fastening means, is a spacing ring 38 providing clearance for an outer locking member 39 secured to the face of the inner clutch member 36 by spot welding or other fastening means. The outer locking member 39 has an oblong opening 40 providing clearance for an inner locking member 41 on which slides the outer locking member 39, 125 130

and the inner locking member 41 has an oblong opening 42 so that the inner locking member may slide on a head 43 loose on the arbor 16 and secured to the compound wheel by spot welding or other fastening means. The constructive arrangement of the locking members 39 and 41 is such that during the eccentric movement of the inner clutch member 36 the locking members are caused to shift, but irrespective of the location of the inner clutch member relative to the outer clutch member it will be impossible for any load sustained by the compound wheel of the arbor 16 to rotate said arbor, thus affording a novel eccentric or irreversible gearing. In other words, the locking members hold the arbor 16 and the inner clutch member relative to the outer fixed clutch member so that the arbor 16 can be only rotated by hand, thus providing an automatic locking mechanism which prevents the sash regulating device from being actuated except by hand power applied by the handle or crank 18 or a like element. The action of the locking members is best understood by reference to Fig. 7 where the inner and outer locking members are shown in position to slide as the inner clutch member is eccentrically moved about in constant mesh with the outer clutch member. The meshing teeth of the clutch members are of such configuration that the arbor 16 can be turned clockwise or counter-clockwise and in either instance held against accidental rotation when released.

The downward movement of the sash 3 will be limited by the lower ends of the guides 2 or any suitable stop placed in the well 4, and the upward movement of the sash 3 may be limited by closing the channel guide of the casing, over the compound wheel, so that the chain extension 26, or 26^a will engage the closed end of the channel guide, thus preventing the operating mechanism from completely releasing the chain.

I attach considerable importance to the fact that the greater part of the sash regulating device is made from stampings, in contradistinction to drop forgings, consequently those parts subjected to wear can be easily hardened and all of the parts readily assembled to provide an extremely light, flat and durable device for adjusting a sash, closure or other movable structure.

While in the drawings there is illustrated a preferred embodiment of my invention, it is to be understood that the structural elements are susceptible to such variations and modifications as fall within the scope of the appended claims.

What I claim is:

1. A clutch for a sash regulating device including an arbor, a wheel, and a flexible member adapted for raising and lowering

a sash:—said clutch being adapted for holding the sash and flexible member in an adjusted position, said clutch comprising a fixed outer clutch member, an arbor actuated inner clutch member normally engaging said fixed outer clutch member, and locking members interposed between said wheel and said inner clutch member normally establishing a driving relation for said wheel by said arbor and precluding any driving of said arbor by said wheel.

2. A clutch as called for in claim 1, wherein said inner clutch member is eccentrically supported by said arbor in said outer clutch member.

3. A clutch as called for in claim 1, wherein one of said locking members is fixed to inner clutch member and the other locking member movably retained by said wheel.

4. A clutch as called for in claim 1, wherein locking members are slidably one within the other and are caused to gyrate relative to said arbor.

5. Clutch means for holding a sash in an adjusted position wherein an arbor and a wheel are included as elements of a sash raising and lowering mechanism, said means comprising a fixed outer clutch member, an arbor actuated eccentric driven inner clutch member in said outer clutch member, and gyrating means establishing a driving relation between inner clutch member and said wheel.

6. Clutch means as called for in claim 5, wherein said gyrating means includes a head loose on said shaft and fixed to said wheel, and members slidably relative to said head, one of said members being fixed to said inner clutch member.

7. The combination with a sash, a chain for moving said sash, an arbor, a wheel loose on said arbor and over which said chain is trained, an outer clutch member, of a clutch, said clutch comprising an inner clutch member normally engaging said outer clutch member and driven by said arbor, and means articulating said inner clutch member and said wheel so that rotation of said arbor may impart rotation to said wheel.

8. A clutch for a sash regulating device including a winding arbor adapted to actuate a wheel, drum or other rotary member to cause adjustment of the sash;—said clutch being adapted to prevent rotation of the winding arbor by movement of the sash, said clutch comprising clutch members, one clutch member being actuated by the winding arbor when the sash is to be adjusted, and locking members adapted to be set in motion by the actuated clutch member to impart movement to the rotary member by which the sash may be adjusted, said locking members cooperating with said clutch members in preventing adjustment of said sash independent of said winding arbor.

9. A clutch for a sash regulating device including a winding arbor which actuates a wheel, drum or other rotary member to cause adjustment of the sash;—said clutch
5 preventing rotation of the winding arbor by movement of the sash, said clutch comprising an irreversible gearing disposed about said winding arbor in a plane parallel to the rotary member by which the sash

is adjusted and adapted to be actuated by 10 said winding arbor for sash adjusting purposes.

In testimony whereof I affix my signature in presence of two witnesses.

GUSTAVE A. CARLSON.
